METHOD OF MAKING INLAID LINOLEUM

William Rowe, Oakland, and Abraham Beck Miller, Berkeley, Calif., assignors to The Paraffine Companies, Inc., San Francisco, Calif., a corporation of Delaware

Application May 22, 1935, Serial No. 22,734

5 Claims. (Cl. 154—26)

This invention relates to the manufacture of flexible covering materials such as linoleum, lin-crusta, and the like, and particularly to the manufacture of so-called "straight-line inlaid" materials of this class.

Among the objects of this invention are: To provide a method of applying tesserae of straight-line material to a backing which affixes them immediately and permanently in place without the necessity of utilizing temporary holding means for this purpose; to provide a method of affixing pattern elements of straight-line material, which are small in dimension and therefore peculiarly subject to deformation, which does not subject 10 said elements to such distortions; to provide a method of attaching to a backing continuous, grid-like pattern elements in the form of a matrix which will serve to position and hold in place later applied tesserae; and to provide a method of 15 making straight-line inlaid linoleums of intricate patterns at a relatively low cost.

Our invention possesses numerous other objects and features of advantage, some of which, together with the foregoing, will be set forth in the 20 following description of specific apparatus embodying and utilizing our novel method. It is therefore to be understood that our method is applicable to other apparatus, and that we do not limit ourselves, in any way, to the apparatus of 25 the present application, as we may adopt various other apparatus embodiments, utilizing the method, within the scope of the appended claims.

Referring to the drawing:

Figure 1 is an isometric view showing a portion 30 of a die of the type used for applying narrow pattern elements in accordance with this invention, together with a section of the covering material in course of manufacture.

Figure 2 is a similar isometric view, partly in 35 section, showing a form of die used in applying larger pattern elements in accordance with this process.

Figure 3 is a schematic diagram illustrating the process as used to apply a reticulated pattern or matrix to a backing, whereon the larger tesserae are later applied in the interstices of 40 said matrix by hand.

Figure 4 is a similar schematic diagram illustrating the application of an entire inlaid pattern 45 to a covering material by this process.

Throughout this specification the term "linoleum" is used as a generic rather than a specific term. As here used it applies to any of the 50 flexible covering materials of the linoleum class, wherein a plastic or semi-plastic coating is ap-

plied to a web or backing, whether said backing be of the conventional treated burlap or of cheese cloth, paper, impregnated felt, or any other suitable material. In like manner, the term "straight-line material" includes any plastic surface coating which may be rolled into sheets from 5 which tesserae may be cut and applied to the backing. In other words, the terms are used as defining the physical properties of the materials rather than their chemical composition. 10

Although the process of this invention was primarily devised for use in connection with the processes described in our copending applications, Serial Nos. 22,732 and 22,733, filed simultaneously with this application, in manufacturing embossed inlaid linoleum of the straight-line class, such, for example, as those representing ceramic tiles, the process is by no means limited to such use, but is equally adapted to the application of 15 patterns of any form and to the formation of level 20 as well as embossed surface linoleums.

Considered broadly, the process of our invention comprises overlaying a suitable backing with a sheet or layer of straight-line linoleum material. Certain portions of the overlying sheet, corresponding to the pattern elements which are to be formed therefrom, are then pressed against the backing with sufficient force to cause them to adhere thereto, the pressure at the edges of the pattern elements in particular being sufficiently 25 great to cut or score the outline of the pattern elements nearly, if not quite, through its entire thickness. The interstitial portions between the pattern elements thus applied remain loose and non-adherent, and are readily stripped away 30 from the backing either mechanically or by hand. Tesserae corresponding to other pattern elements are then applied in interstitial portions of the pattern, either by a repetition of the same process or in any other desirable manner, and the 35 entire covering is then subjected to a sufficient pressure to cause a slight plastic flow of the tesserae which consolidates them with the backing and with the edges of the contiguous tesserae, 40 whereafter the entire material is subjected to 45 the requisite curing process.

One of the most useful applications of this process is in the manufacture of linoleum in tile patterns. In the process described in our copending applications above referred to, the grid-like network of narrow interconnected lines representing the mortar between the tiles is first applied to the backing as a matrix, and the tesserae representing the tiles themselves are 50 later laid in the interstices of the matrix, the 55

tesserae being positioned by the matrix and held in place by gravity and edge friction. The process to which this application refers is especially adapted to the application of the matrix to the backing, and is illustrated schematically in Figure 3.

In this figure the backing 1 is supplied from a roll 2, and on top of it is laid the sheet 3 of straight-line material, preferably directly from 10 a pair of calendar or feed rolls 4. The straight-line material 3 may be the usual linoleum composition compounded principally of blown linseed oil, rosin and cork, or it may be of any other suitable compound which may be handled in the 15 same manner, such as the composition described in the companion case, Serial No. 22,733 above referred to.

The backing with its loosely overlying sheet of straight-line material is next passed under a 20 press 5 which carries the cutting and affixing die 7. In the schematic diagram, this press is shown of the roller type, which form of press lends itself particularly to a continuous process, but it is specifically to be understood that the form 25 of press which is used for applying the linoleum material to the fabric is immaterial, and may be any standard press such as is used for either cutting or printing.

Where the patterns to be applied constitute 30 a matrix of the type described above, the die may conveniently be of the form shown in Figure 1. The cutting element in this case is preferably a strip of steel 8 whose lower or active surface is channeled by groove 9, leaving the sharp peripheral cutting edges 10. The groove 9 has a depth which is equal to or slightly less than the thickness of the linoleum material 3 when compacted, and the press is adjusted so that the cutting edges 10 do not penetrate the layer of fabric 40 1. It is immaterial whether they touch the fabric or clear it slightly, since when the press operates the action of the die is to force the material embraced by the groove simultaneously against the fabric backing and toward the center of the pattern element, and when the die is withdrawn it leaves the material of the layer 3 deeply scored by the grooves 12 and strongly adherent to the backing in those portions lying between these two grooves. The linoleum material, 45 whether cut completely through or not, has nonetheless been subjected to so strong a shearing action immediately beneath the cutting edges 10 as practically to leave those portions of the sheet which were not subject to the action of the die 50 completely free, so that they may be stripped off readily by hand or machine.

It is to be noted that a die of this character applies the greatest pressure to the figure elements thus punched out immediately adjacent their 60 edges. This assures that the edges will be strongly adherent to the backing, even though the central portions of the figure may not be, and it follows that it is thus possible to supply sufficient pressure to attach the particular pattern elements 65 even though they may be so large that the press would not have sufficient capacity to apply the requisite pressure throughout the entire area of the figure.

It is also to be noted that this type of die, although preferable for the particular use specified, 70 is not an essential to the process. Where the figure elements are large or curvilinear in outline, dies formed as shown in Figure 2 are equally applicable, and frequently preferable. Such dies 75 are formed by inserting sharp-edged steel or brass

rules 13 into a block or backing of hard wood 14, the backing being cut away outside of the rule so as to leave a table or raised portion 15 within the figure, whereas the portion 17 lying outside of the figure or pattern element is at a lower level. 5 The table 15 applies the requisite pressure to cause adherence of the material to the backing.

Furthermore, it is possible to utilize the process without any projecting cutting edges whatsoever upon the die, if the backing 1 has sufficient 10 strength in shear, and is somewhat resilient. In this case, the die may be in the form of a simple punch having a flat surface and a substantially rectangular cutting edge around its periphery. The overlying linoleum material is usually so weak 15 in shear that the yielding of the layer 3 and the backing under the application of the pressure are sufficient to sever the pattern from the remainder of the sheet. We prefer, however, to utilize the projecting cutting edges as described. 20

The interstitial portions of the sheet 3 which are non-adherent to the backing, having been stripped away, their places may be filled by tesserae 20, previously cut to fit the interstices of the matrix, whereafter the entire covering is 25 subjected to pressure in a suitable press, typified in the diagram by a roller 22, against which the linoleum is held by means of a pressure belt 23. Again, any form of press suitable to the 30 manufacture of linoleum materials of this class may be used. Sufficient pressure is applied in the press to cause a slight flow of the linoleum material comprising the various pattern elements, consolidating the contiguous edges of the 35 various tesserae and also the tesserae against the backing. No change in the conventional curing processes is made.

The process is not limited to the application of any single group of figure elements, but, after one color of tesserae has been applied, the process 40 may be repeated with another color as is shown in Figure 4. This merely requires a duplication of certain of the parts, such as the feed rolls 4' which feed the sheet 3' of straight-line material to be affixed by the press roller 5' which carries the cutting and affixing die 7'. The remaining portions of the diagram are identical with those of Figure 3, and these elements may be duplicated as often as is necessary 45 to apply the requisite number of color elements to the pattern. The dies 7, 7', etc., are of course, complementary, so that the portions affixed in one operation coincide with those which are stripped away in the preceding and 50 succeeding ones. 55

We claim:

1. The method of making covering materials of the linoleum class which includes the steps of overlaying loosely a sheet of uncured straight line linoleum material upon a backing, pressing 60 limited sharply defined portions of said sheet corresponding to the pattern elements of the completed covering against said backing to cause adherence thereto by said portions and to cause shearing of the linoleum material at the boundaries of said adherent portions, and stripping the remaining non-adherent portions of said sheet from said backing.

2. The method of making covering materials of the linoleum class which includes the steps 70 of overlaying loosely a sheet of uncured straight-line linoleum material upon a backing, simultaneously pressing limited portions of said sheet corresponding to pattern elements of the completed covering against said backing to cause 75

adherence thereto and scoring through a major portion of the thickness of said sheet around the outline of said pattern elements, and stripping from said backing the non-adherent portions of said sheet between the adherent portions.

3. The method of making covering materials of the linoleum class which includes the steps of overlaying loosely a sheet of uncured straight-line linoleum material upon a backing, applying pressure to limited areas of said sheet corresponding to pattern elements downwardly against said backing and inwardly toward the central portions of said pattern elements to cut through the major portion of the thickness thereof and affix said pattern elements to said backing, removing the unwanted portions of the linoleum material from the backing, positioning tesserae corresponding to the remaining pattern elements in the interstices between said first-mentioned pattern elements, and applying pressure to the entire surface to cause sufficient plastic flow of said pattern elements to fill the cracks therebetween.

25 4. The method of making covering materials of the linoleum class which includes the steps of overlaying loosely a sheet of uncured straight-

line linoleum material upon a backing, simultaneously punching tesserae corresponding to pattern elements from said sheet and pressing said tesserae against said backing to cause adherence thereto, removing the unwanted portions of the linoleum material from the backing, fitting additional tesserae between the first applied tesserae, and applying sufficient pressure to all of said tesserae to cause consolidation of the adjacent edges thereof.

5 5. The method of making covering materials of the linoleum class which includes the steps of overlaying loosely a sheet of uncured straight-line linoleum material upon a backing, simultaneously punching tesserae corresponding to pattern elements from said sheet and pressing said tesserae against said backing to cause adherence thereto, removing the unwanted portions of the linoleum material from the backing, repeating each of said steps to apply additional tesserae 15 intermediate said first-named tesserae, and applying pressure simultaneously to adjacent tesserae to cause a flow thereof consolidating their contiguous edges.
